[57] CLAIM

The ornamental design for skylight flashing, as shown and described.

DESCRIPTION

FIG. 1 is a perspective view of skylight flashing, incorporated into a complete tubular skylight system as its environment, which is for illustrative purposes only and forms no part of the claimed design, showing a new design in accordance with the present invention;

FIG. 2 is a top left view thereof;

FIG. 3 is a left side view thereof;

FIG. 4 is a front view thereof;

FIG. 5 is a back view thereof;

FIG. 6 is a right side view thereof; and,

FIG. 7 is a top right view thereof.
